US00D797423S

(12) **United States Design Patent** (10) **Patent No.:** **US D797,423 S**
Bischoff et al. (45) **Date of Patent:** **** Sep. 19, 2017**

(54) **SHOE**

(71) Applicant: **Reebok International Limited**, London (GB)

(72) Inventors: **Robert Bischoff**, Attleboro, MA (US); **Matthew Boudreau**, North Attleboro, MA (US)

(73) Assignee: **Reebok International Limited**, London (GB)

(**) Term: **15 Years**

(21) Appl. No.: **29/544,149**

(22) Filed: **Oct. 30, 2015**

(51) LOC (10) Cl. **02-04**

(52) U.S. Cl.

U.S. Appl. No. 29/544,150, filed Oct. 30, 2015; Bischoff et al.

Primary Examiner — T. Chase Nelson

(74) Attorney, Agent, or Firm — Sterne, Keesler, Goldstein & Fox P.L.L.C.

(57) **CLAIM**

The ornamental design for a shoe, as shown and described.

DESCRIPTION

FIG. 1 is a bottom perspective view of a shoe showing the claimed design;

FIG. 2 is a top plan view thereof;

FIG. 3 is a bottom plan view thereof;

FIG. 4 is a side view thereof;

FIG. 5 is another side view thereof;

FIG. 6 is a front view thereof; and,

FIG. 7 is a rear view thereof.

The broken lines in the figures show portions of the shoe that form no part of the claimed design.

1 Claim, 6 Drawing Sheets
